UNITED STATES PATENT OFFICE.

FREDERICK J. MILLER, OF BROOKLYN, NEW YORK.

BANJO.

SPECIFICATION forming part of Letters Patent No. 310,906, dated January 20, 1885.

Application filed January 22, 1884. (No model.)

To all whom it may concern:

Be it known that I, FREDERICK J. MILLER, a citizen of the United States of North America, and a resident of Brooklyn, county of 5 Kings, State of New York, have invented a new and useful Improvement in Banjos, of which the following is a specification.

The objects of this invention are to improve the tone, quality, and finish of a banjo, and 10 the invention consequently embraces several improvements, that are hereinafter fully set forth.

Reference is to be had to the accompanying drawings, forming part of this specification, 15 in which similar letters of reference indicate corresponding parts in all the figures.

Figure 1 is a plan of my improved banjo, with parts broken away to exhibit other parts. Fig. 2 is a side elevation of a portion of the 20 handle with hollow metal nut affixed. Fig. 3 is a cross-section on line $x-x$, Fig. 1. Fig. 4 is a longitudinal section on line $y-y$, Fig. 1. Fig. 5 is a cross-section on line $z-z$, Fig. 1, looking in the direction of the arrow, and 25 showing my improved stretching-clamp. Fig. 6 is an enlarged elevation of a portion of the banjo-rim, showing the tail-piece in elevation. Fig. 7 is an enlarged sectional elevation on line $x'-x'$, Fig. 4, showing a modified tubular 30 metallic outlet in section. Fig. 8 is an enlarged sectional elevation showing my improved metallic outlet in section. Fig. 9 is an enlarged elevation of a portion of the banjo-rim, showing my improved clamp for stretching 35 the banjo-head. Fig. 10 is an enlarged cross-section on line $x-x$, Fig. 4. Fig. 11 is a plan of the turn-buckle used on a modification 40 of the improved clamp shown in Fig. 12. Fig. 12 is an enlarged sectional elevation of a portion 45 of a banjo-rim, showing a side elevation, partly in section, of my improved stretching-clamp in place, on line x^2-x^2 , Fig. 1. Fig. 13 is a partly-sectional side elevation of a portion 50 of the banjo, showing vibratory helices attached. Fig. 14 is a plan of the same. Fig. 15 is an enlarged side elevation of my improved stretching-clamp.

The rim A of my improved banjo is constructed of wood, cork, or other non-metallic 55 substance, as shown at a, and is covered on both sides and top with sheet metal, b, to give it stiffness

and keep it in shape. Said sheet-metal covering b may be applied in a single piece, as indicated in Fig. 7, or in sections that may be soldered together, as indicated at e, Fig. 8, 55 and, being raised above the upper edge of the wood a, forms entirely around the banjo-rim a tubular chamber, d, by which the resonant power of the instrument is increased. The volume of sound is increased by means of a 60 sounding-board, B, consisting of a disk of sheet metal having, preferably, a central aperture, f', and a downwardly-projecting edge flange, g, by which it is secured, in a horizontal plane, by means of bolts or other devices, within the lower part of the banjo-rim, beneath the head G. Apertures h are 65 commonly made in a banjo-rim for sound-outlets; but about such apertures the wood is apt to check or split, and thereby impair the instrument. To avoid this I fit in each aperture h a metallic eyelet or thimble, i, as shown in Fig. 7, or, preferably, I use for this purpose a trumpet-shaped thimble or tube, as shown in Fig. 8 at i', the flaring mouth of which projects beyond the banjo-rim, and because of 70 its shape increases the volume of sound. The arm C is for the most of its length made hollow, as shown at i², to increase the resonance 75 of the instrument, and is preferably provided with sunken frets k, that may extend all the way or only partly across, as may be deemed best, and that connect with the cavity i². These sunken frets k enable the operator to run the hand more freely down the 80 arm, and to feel with more accuracy the points at which to press the strings. The nut or post l, over which the banjo-strings are drawn, is made hollow and of metal in order to increase 85 the vibrations of said strings. That prolongation, C', of the arm C which passes through the banjo-rim is tubular, and preferably made of metal, and may be perforated, as shown at l', to increase the volume of sound, and on the sides of this prolongation C', within the 90 banjo-rim, may be secured helices m, for increasing the musical vibrations when the instrument is played. The clamps E are attached to the metal straining-ring D by solder or rivets, as indicated in Fig. 9, instead 95 of, as is customary, by hooks, that are liable to catch in the garments of the operator. The

clamps or tightening-screws ordinarily used for drawing down the straining-ring, and thereby stretching the banjo-head, are so constructed that they also catch in the clothes of the operator and cause much inconvenience. To avoid this objection I construct my improved clamps E, each of which consists of a rod, n, flattened at the upper end, and having a right or left screw-threaded shank or prolongation, 10 and of a lug, n', whose reduced end is screw-threaded in the opposite direction from that of the rod-shank, and whose head is perforated at right angles to its length. These two parts have their screw ends connected by a turn-buckle, n². When in place, with the upper end of the rod n riveted to the ring D, and the lug n' secured to the banjo-rim by screws n³, the turning of the turn-buckle n² will stretch or loosen the head, as the case may be. A 15 modification of this clamp is shown in Figs. 9 and 12, wherein a hook, o, is substituted for the lug n', and is designed to be engaged about the lower edge of the banjo-rim, as shown. The tail-piece H is an angle-plate of metal, bolted, riveted, or otherwise suitably secured to the ring D, as shown.

I am aware that violins have been provided with a metallic sounding-board, and also that it is common to provide banjos with wooden 30 sound-boards, and do not claim such, broadly, as in all such cases the construction and arrangement are essentially different from mine.

Having thus described my invention, I claim as new and desire to secure by Letters Patent—

35 1. In a banjo, a rim constructed, substantially as herein shown and described, of a non-metallic material, covered and strengthened by a metallic sheathing in intimate contact

with both sides of and extending over the top of said rim, substantially as set forth. 40

2. In a banjo, a rim composed of a non-metallic material inclosed within and filling the space between the sides of a sheet-metal case, leaving a tubular chamber around the upper edge of said rim, as and for the purposes 45 specified.

3. The combination, with a banjo head and rim, of a centrally-apertured metallic sounding-board having a downwardly-projecting flange, g, substantially as herein shown and 50 described, and means for securing said sounding-board horizontally to the rim beneath the head, as set forth.

4. A banjo-rim provided with a metallic sheathing, in combination with metallic tubes 55 passing through said rim and sheathing, and performing the double function of uniting said rim and sheathing and of serving as sound-outlets, substantially as shown and described.

5. In a banjo, the combination, with an arm, C, and hollow metallic arm prolongation C', of vibratory helices m, attached to said prolongation C', substantially as herein shown, and for the purposes described. 60

6. In a banjo, a hollow arm provided with 65 transverse slots k, to serve the double function of guides and sound-outlets, substantially as described.

In testimony that I claim the foregoing as my invention I have signed my name, in presence of two witnesses, this 15th day of January, 1884. 7c

FRED. J. MILLER.
